(57) **CLAIM**

The ornamental design for a lifting apparatus, as shown and described.

DESCRIPTION

FIG. 1 is a perspective view of a lifting apparatus showing our new design;

FIG. 2 is a front view thereof;

FIG. 3 is a right side view thereof;

FIG. 4 is a top plan view thereof;

FIG. 5 is a bottom plan view thereof; and

FIG. 6 is a cross sectional view taken along with line 6—6 in FIG. 4 thereof; and,

FIG. 7 is an illustrative view thereof.

A rear view of the lifting apparatus is symmetrical to the FIG. 2. A left side view of the lifting apparatus is symmetrical to the FIG. 3.

The broken line showing of a drum and chain in FIG. 7 is for illustrative purposes only and forms no part of the claimed design.
